CIGAR LIGHTER OR THE LIKE

Marcel Quercia, Paris, France, assignor to Flaminaire
Marcel Quercia, Paris, France, a corporation of France

Filed Nov. 9, 1960, Ser. No. 62,790

Term of patent 14 years

(Cl. D48—27)

Fig. 1.

Fig. 2.

Fig. 3.

Fig. 4.

Fig. 5.

Fig. 6.

Fig. 7.

FIG. 1 is a side elevation of a cigar lighter or the like showing my new design, the appearance of the opposite side being substantially the same;

FIG. 2 is a view in elevation thereof as seen from the left of FIG. 1;

FIG. 3 is a view in elevation thereof as seen from the bottom of FIG. 1;

FIG. 4 is a view in elevation thereof as seen from the right of FIG. 1;

FIG. 5 is a view in elevation thereof as seen from the top of FIG. 1;

FIG. 6 is a view in elevation thereof as seen from the top left of FIG. 1; and

FIG. 7 is a view in elevation thereof as seen from the bottom right of FIG. 1.

The essential features of the design reside in the portions shown in full lines on the drawing.

I claim:

The ornamental design for a cigar lighter or the like, as shown and described.
